UNITED STATES PATENT OFFICE.

ERASTUS BOYDEN AND GEORGE H. PILLSBURY, OF LOWELL, MASS.

IMPROVEMENT IN ELECTRO-MAGNETIC STOP-MOTIONS FOR DRAWING OR ROVING MACHINERY,

Specification forming part of Letters Patent No. 173,888, dated February 22, 1876; application filed January 12, 1876.

To all whom it may concern:

Be it known that we, ERASTUS BOYDEN and GEORGE H. PILLSBURY, of Lowell, of the county of Middlesex and State of Massachusetts, have invented an Electro-Magnetic Stop-Motion for Machinery for the Manufacture of Drawing or Roving; and do hereby declare the same to be fully described in the following specification and represented in the accompanying drawings, of which—

Figure 1 denotes a front elevation, Fig. 2 an end view, Fig. 3 a top view, and Fig. 4 a longitudinal and horizontal section, of our stop-motion.

In carrying out our invention, as shown in the drawings, we make use of an electro-magnet, its armature, and circuit-wires, which we combine with the roving or drawing guide, and with a latching apparatus of a shipper; the whole being so that whenever the roving or drawing may become broken or run out, the guide shall rise and close the circuit, and thereby cause the magnet to attract and move the armature and set free the latching apparatus, so as to allow the shipper to be operated by its spring, in order to effect the shifting of the belt from a driving to a loose pulley, and the consequent stoppage of the machine. Furthermore, we have combined with the electro-magnet, its circuit-wires, armature, the guide, the latching mechanism, and the shipper, means or mechanism for opening the circuit on retreat of the shipper, and keeping such circuit open while the drawing or roving machine is stopped, such mechanism serving to close the circuit during the advance of the shipper. When the guide is depressed and the shipper advanced, the circuit becomes open or broken, and the armature falls away from the magnet, to aid in effecting the latching of the shipper.

In the drawings, the shipper is shown at A as arranged to slide rectilinearly through guides a a, extending from a support-piece, T, such shipper being provided with a spring, B, for retracting it or forcing it backward, to cause it, when in use, to move the driving-belt from the fast to the loose pulley of the roving or drawing frame or machine. There is also applied to the said shipper a spring-latch, C, formed as shown, to catch upon

the shorter arm of a bent lever, D, arranged as represented. Over the end of the longer arm of the bent lever is a stud, b, which projects rearward from a gravitating lever or trigger, E, shaped as shown, the shorter arm e of which is heavier than the longer arm d of it. This trigger is pivoted in a bracket, e, its longer arm being extended a short distance underneath the end of a pendulous armature, F, of an electro magnet, G. The armature stands nearly vertical, and turns on a pin, f, projecting from a plate, g. Furthermore, there extends from the upper part of the armature, and over the electro-magnet, a weight or arm, h, which serves to throw the armature off the magnet whenever the circuit is broken, the extent of such movement of the armature being determined by a stop, i, underneath the arm h. The roving or drawing guide is shown at H, in the form of a furcated bent lever, having its fulcrum at k. The unfurcated arm of the lever is the heavier, and has a small wire, l, extended from it, to operate with an anvil, m, connected with one extremity of the electro-magnetic circuit-wire n, the other circuit-wire, o, being extended from a stationary metallic standard, P, connected with the guide by a metallic link, q. If, now, we suppose the sliver or roving to be in the fork of the guide, and intact, and the fork, by the draft on the roving or sliver, to be depressed so as to raise the wire l off the anvil m, the circuit will be broken or open, it being understood that the circuit-wires are to be connected with or applied to a galvanic battery. On advancing the shipper far enough, its latch c will catch upon the lower arm of the bent lever, the retractive force of the spring of the shipper causing the bent lever to be turned on its fulcrum up against the escapement or stud b of the trigger E, whereby the longer arm of the said trigger will be moved up against the lower end of the armature. Under this condition of the parts the shipper will be estopped in position, and will remain so while the sliver or roving may hold down the guide; but should the sliver or roving become broken or run out, so as to allow the guide to rise, its heavier arm will descend until the wire l may reach the anvil m; which having taken place, the circuit will be closed,

and the armature will be drawn toward the magnet and off the trigger. This latter, rising up, will carry the escapement-stud off the bent lever, and allow it to be thrown up clear of the spring-latch of the shipper, in which case the spring of the shipper will force such shipper backward, and by it effect the stoppage of the machine. Over the shipper, and below the electro-magnet, there is a circuit breaker and closer, S, to be actuated by the shipper. It consists, mainly, of a metallic spring, *w*, fastened at one end by the support-piece *T*, and provided at its free end with a piece of hard rubber or vulcanite, *r*, carrying a metallic button, *s*, which is to operate with a similar button, *t*. One of the circuit-wires is separated, and the ends, at the separation, are respectively attached to the two buttons, the same being as shown in the drawings. The said circuit breaker and closer further consists of a stud, *u*, which extends up from the shipper, and, while the shipper is being advanced, is carried against the spring *w*, so as to move it inward, and its button *s* against the button *t*, and close the circuit. On the shipper being forced back by its spring, the spring *w* will be set free, and will move the button *s* away from the button *t*, and thus the circuit will be open or broken. Thus, while the machine is stopped, the battery will cease its action.

We contemplate the application of our electro-magnetic stop-motion to various kinds of machinery used for making drawing, roving, or yarn, or in the manufacturing of textile-fabrics, the guide, in its construction, being varied, as circumstances may require.

We are aware that an electro-magnetic stop-motion for machinery for spinning is not new, such being described in the United States Patent No. 138,993, dated May 20, 1873. Our stop-

motion, though, like that, containing a mechanism by which, when a thread may break, the circuit will be closed, and the magnet be caused to operate its armature, to cause it to set free the shipper to enable its spring to actuate it, differs materially therefrom in its construction, arrangement, and operation of its parts, especially in the latching mechanism, and in the arrangement, construction, and mode of operation of the circuit breaker and closer S, which is entirely disconnected from the yarn-guide lever H, and in no respect aids in moving such relatively to the yarn, as does the device or yoke described and shown in the said patent. Our latching mechanism, as described, produces so little pressure on the armature that a very small amount of electric force is required to operate such armature.

We claim as our invention as follows:

1. The electro-magnetic stop-motion, substantially as described, composed of the electro-magnet G, its circuit *n o*, armature F, drawing or roving guide H, shipper A, operative spring B, latch C, and levers D E, all arranged and applied as set forth.

2. We claim the combination of a circuit breaker and closer, S, (so separated from the yarn-guide lever H as, while in movement, to be incapable of moving it either way on its fulcrum,) with the electro-magnet G, its circuit *n o*, armature F, the drawing or roving guide H, the shipper A, its operative spring B, and latch or latching mechanism C D E *b* all applied and to operate substantially as specified.

ERASTUS BOYDEN.

GEORGE H. PILLSBURY.
